REFRIGERATOR

Theodore W. Rundell, Jenkintown, Pa., assignor,
by mesne assignments, to Philco Corporation,
Philadelphia, Pa., a corporation of Pennsyl-
vania

Application August 3, 1940, Serial No. 350,746

2 Claims. (Cl. 62—89)

This invention relates to new and useful improvements in domestic refrigerators and more particularly to novel closure devices for the evaporator units of such refrigerators.

Prior to the present invention, the closures or doors for the evaporators in domestic refrigerators have, for the most part, been composed of sheet metal material and these have necessarily been spaced substantially in front of the evaporator unit so that they are not sufficiently chilled to cause the condensation of moisture thereon. Spacing of the door from the front of the evaporator unit in this manner does not effectively seal the evaporator and, therefore, an appreciable quantity of air is permitted to circulate through said evaporator. Hence only a small temperature differential is maintainable between the air in the evaporator and that in the main food storage compartment and, furthermore, water and foods being frozen or chilled within the evaporator quite often take on odor and taste of food-stuffs within the main food storage compartment.

Too, the use of sheet metal evaporator doors causes the adjacent portion of the inner panel of the main refrigerator door to become chilled to such a degree that when the refrigerator door is opened or moist air contacts the cold portion of its inner panel, moisture will be condensed and objectionable sweating on the inner door panel will take place.

With the foregoing observations in mind, the principal object of the invention is to provide for domestic refrigerators a novel and distinctive evaporator and closure therefor which may be employed advantageously for the freezing and preservation of foodstuffs and wherein all of the aforementioned objections and disadvantages are effectively overcome.

Another object of the present invention is to provide an evaporator of the character set forth having novel closure means in conjunction therewith constructed and arranged so as to eliminate sweating thereof and, at the same time, permit the maintenance of a greater temperature differential between the air in the evaporator and in the main food storage compartment while also eliminating any possibility of water and foods in the evaporator taking on the odor or taste of foods in said main food storage compartment.

Still another object of the invention is to provide an evaporator having closure means of the character described through which may be viewed the interior and contents of said evaporator.

A further object of the invention is to provide

evaporator closure means of the type described which is quite novel and distinctive and yet less expensive to manufacture than evaporator closure means heretofore employed.

5 These and other objects of the invention and the various features and details of the construction and function thereof are hereinafter more fully set forth and described and shown in the accompanying drawing, in which:

10 Figure 1 is a partial view in perspective of a domestic refrigerator having an evaporator embodying the present invention.

Figure 2 is a view in front elevation of a refrigerator door thereof being open to show the evaporator and its novel closure member, and

15 Figure 3 is an enlarged diagrammatic view in section taken on line 3—3, Figure 2.

The invention, among other things, consists essentially in the discovery that by employing an evaporator closure member or door having substantially non-heat conducting and non-hygrosopic properties, I am able effectively to substantially close the evaporator against the circulation therethrough of air from the main food storage compartment and at the same time eliminate undesirable sweating of the closure member and of the main refrigerator door.

20 Another equally important feature provided by the invention is that closure member or door such as this may be made transparent and thus afford the further advantage of being able to view and inspect the contents of the evaporator without the necessity of opening the said evaporator door.

25 Referring now to the drawing, reference numeral 1 designates, generally, a domestic refrigerator cabinet having a food storage compartment 2 and a door or like closure 3 for access to the latter. Located within the food storage compartment 2 is the usual refrigerating evaporator 4 and in the form of refrigerator shown said evaporator is mounted in the upper left hand corner of the compartment 2. Disposed in spaced horizontal relation between the evaporator 4 and the bottom of the compartment 2 are the usual food supporting shelves 5 the uppermost one of which may, if desired, support a meat or other storage receptacle 6 immediately beneath the evaporator 4 as shown.

30 The evaporator 4 may be of the conventional type comprising a sheet metal shell of generally U or rectangular shape open at the front and within which there are preferably provided one or more shelves, partitions or the like arranged so as to form with said shell a plurality of com-

partments therein open at the front of the evaporator for the reception of foodstuffs to be frozen and stored. Preferably, the rear and top walls of the evaporator should be substantially closed. Secured to the front of the evaporator shell by means of a hinge 7 is a door or like closure member 8 which is arranged, when closed, entirely to cover the front of said evaporator shell and substantially seal the compartments therein against the circulation of air thereto. As clearly illustrated in Fig. 3, the peripheral edge portions of the closure member 8 extend rearwardly parallel to and closely adjacent the outer walls of the evaporator 4 for a short distance adjacent the front portions of said walls and serve to substantially seal the inside of the evaporator unit against the circulation of air therethrough from the food storage compartment of the refrigerator. In instances where a meat or other receptacle 6 is disposed immediately beneath the evaporator 4, as previously described, the door 8 may be extended downwardly to cover the front of said receptacle 6 in the manner shown in the drawing.

In accordance with the present invention the door or closure member 8 may be molded of suitable plastic material such as, for example, polystyrene or other non-heat conducting, non-hygrosopic plastic molding composition. In addition, I prefer that the plastic molding composition employed be such as will produce a molded article that is transparent and substantially colorless. In the case of a transparent door or closure member, the edges thereof may be etched or otherwise treated or coated so as to render said edge portions translucent or opaque as indicated at 9 for the purpose of concealing from view the forward edges of the side and bottom walls of the evaporator shell and also for the purpose of generally enhancing the appearance of the said door member. Likewise, shelves and partitions within the evaporator shell may be concealed from view in a similar manner, or by means of strips 10 of material such as metal secured to the outer surface of the door in positions corresponding to the evaporator shelves and partitions, and these strips 10 as well as any other form of shelf and partition concealing means may be utilized as a background or mounting for legends descriptive of the foods stored in each of the several compartments of said evaporator and in the receptacle 6 immediately therebelow.

From the foregoing, it will be seen that the present invention provides a novel door or closure member for the evaporators of domestic refrigerators which is of distinctive appearance and which permits the contents of the evaporator to be viewed and inspected without the necessity of opening the evaporator door.

In addition, and no doubt of greater impor-

tance is the fact that the door or closure member 8, being of non-heat conducting and non-hygrosopic material, may be placed close to the front of the evaporator shell to effectively prevent the circulation of air into the evaporator without causing appreciable sweating of the door. Thus it is possible to eliminate sweating of the evaporator door and at the same time maintain a greater temperature differential between the air in the evaporator and in the main storage compartment and prevent water and foods in said evaporator from taking on or acquiring odors and tastes of foodstuffs in said main refrigerator compartment.

Too, another advantage accruing from the present invention is that the non-heat conducting property of the evaporator door 8 effectively eliminates condensation of moisture and sweating of the portion of the inner panel of the refrigerator door 3 adjacent the evaporator.

While a particular embodiment of the invention has been herein illustrated and described, it is not intended that the invention be limited to such disclosure but that changes and modifications may be made thereto and incorporated therein within the scope of the annexed claims.

I claim:

1. In a refrigerator comprising a cabinet having a food storage compartment therein with a door at the front of said compartment for access thereto; a refrigerating structure including an evaporator unit disposed within said food storage compartment and having an open front disposed adjacent the inner surface of said door when said door is closed; and a unitary closure member for the front of said evaporator unit composed of non-heat conducting material and arranged to reside closely adjacent the open front of said evaporator unit and between said unit and the inner surface of said closed door, said member completely covering the front of said evaporator unit and providing between said unit and the inner surface of said closed door a non-heat conducting shield operable to minimize the chilling of the inner surface of said closed door by said evaporator unit to thereby prevent the condensation of moisture on said inner surface, said closure member having its peripheral edge portions extended rearwardly parallel to and closely adjacent the outer walls of the evaporator unit for a short distance adjacent the front portions of said walls to substantially seal the inside of the evaporator unit against the circulation of air therethrough from the food storage compartment of the refrigerator.
2. A refrigerator as claimed in claim 1 wherein the closure member is composed of material having substantially non-heat conducting and non-hygrosopic properties.

THEODORE W. RUNDELL.
